United States Patent Office.

STEPHEN J. BATCHELDER, OF MANCHESTER, NEW HAMPSHIRE.

Letters Patent No. 79,187, dated June 23, 1868.

IMPROVEMENT IN LAMP-EXTINGUISHERS.

The Schedule referred to in these Letters Patent and making part of the same.

TO WHOM IT MAY CONCERN:

Be it known that I, STEPHEN J. BATCHELDER, of Manchester, in the county of Hillsboro, and State of New Hampshire, have invented an Improved Lamp-Extinguisher; and I do hereby declare that the following is a full, clear, and exact description thereof, which will enable others skilled in the art to make and use the same, reference being had to the accompanying drawings, forming a part of this specification, in which—

Figure 1 represents a plan or inside view of this invention.

Figure 2 is a side elevation, with a transverse section of the same.

Similar letters of reference indicate like parts.

This invention relates to a burner used for kerosene or other light hydrocarbon-oils, to which a vapor-tube is attached.

The invention consists, first, of a flanged cap or extinguisher, fitting closely over the wick and vapor-tubes, when the same are closed; second, of a flat spring or band, embracing the wick-tube, which, by its pressure on the spindle-crank, to which the cap or extinguisher is attached, keeps the cover firmly in its place, when closed over the tubes.

Fig. 1. Letter A represents the flanged cap or extinguisher closed over the wick and vapor-tubes. B represents the spindle-crank; C, the flat spring or band, embracing the wick-tube.

Fig. 2. D, the base or support for the spindle-crank B, which operates the cap A, and which is attached to the wick-tube by means of solder or rivets.

It will be readily understood that the advantage of turning a flange on the cap or extinguisher is, that when closed over the tubes, it fits more tightly, and its rotation is prevented.

One serious objection to the burning of light hydrocarbon-oils for illuminating purposes, especially those in which naphtha enters is the escape of gases or vapors after extinguishing the light, and particularly when lamps containing such compounds are placed in warm situations, such as on the mantel-shelf and elsewhere. This invention obviates, as will be readily seen, this objection, by preventing the escape of gases and vapor, both from the wick and vapor-tube.

Having thus described my invention, I claim as new, and desire to secure by Letters Patent—

The flanged cap or extinguisher A, so constructed as to cover the wick and vapor-tubes F and G, in combination with the flat spring or band C, embracing the wick-tube F, and operating in connection with the spindle-crank B.

The above specification of my invention signed by me, this 3d day of December, 1867.
